ATTORNEY.

UNITED STATES PATENT OFFICE.

CORNELIUS JORDAN, OF WEEHAWKEN, NEW JERSEY, ASSIGNOR TO E. H. KLUGE
WEAVING COMPANY, OF NEW YORK, N. Y., A CORPORATION OF NEW YORK.

MECHANISM FOR PACKAGING LABELS AND THE LIKE.

1,231,028.

Specification of Letters Patent. Patented June 26, 1917.

Application filed November 14, 1916. Serial No. 131,324.

To all whom it may concern:

Be it known that I, CORNELIUS JORDAN, citizen of the United States, residing at Weehawken, in the county of Hudson and 5 State of New Jersey, have invented certain new and useful Improvements in Mechanism for Packaging Labels and the like, of which the following is a specification.

Machines are in use for cutting off from 10 a strip woven, printed or the like labels and then folding back the ends thereof, the final operation being the passing of the labels between coacting rolls which crease or fold the suitably turned back ends into definite 15 folds. A machine of this kind is shown in Letters Patent No. 1,104,316, to A. Rosenthal. Heretofore the formed labels have been delivered indiscriminately into or onto some suitable container, so that a tedious 20 hand-operation was necessary to get them into an orderly arrangement in compact packs for shipment and the convenience of the consumer.

The object of this invention is to provide 25 means whereby the labels (or it may be other flat articles of manufacture) may be one after another, as delivered by the forming machine, formed into an orderly pack, the same being designed in the adaptation of 30 the invention herein shown and described by way of example as an attachment to a machine whose final operation is to pass the labels or other pieces of material between revolving rolls.

35 In the accompanying drawings,

Figure 1 is a plan of the mechanism, showing so much of the machine to which it forms an attachment as includes the said rolls and a certain cam-shaft;

40 Fig. 2 is a side elevation, partly in section, of what appears in Fig. 1;

Fig. 3 is a plan, on a larger scale, of the mid-portion of said mechanism;

Fig. 4 is a longitudinal sectional view of 45 what appears in Fig. 3;

Fig. 5 is a sectional view on line 5—5 of Fig. 2;

Figs. 6 and 7 are sectional views on lines 6—6 and 7—7 of Fig. 4; and,

50 Fig. 8 is a perspective view of the carton.

The cutting and folding machine *a* has the rolls *b* for creasing into permanent form the suitably bent back ends of the labels (A, Fig. 6) journaled on horizontal 55 axes, the cam-carrying shaft *c* journaled

parallel with the rolls, and the two-armed lever *d*—*e*, one arm *d* of which bears against the cam on said shaft *c*. The rolls are formed with shallow peripheral grooves *b'*. The shaft and rolls are geared together by 60 suitable means (not shown).

A work-support *f*, secured at one end to the machine *a* and having a supporting leg *g* at its outer end, has on the top face thereof (it being a plate in the present instance) 65 lateral gage members *h* laterally adjustable and an end gage member *i* longitudinally adjustable. These receive between them, as shown, the outer carton member *B* of a carton (Fig. 8) whose inner member *C* is 70 telescoped into the member *B* and has one end closed and the other open, member *B* having a closable flap *C'*. At the outset of forming a pack of the labels the inner member *C* protrudes for nearly its whole 75 length from the outer member *B* (Fig. 4), resting on the work-support.

A frame for the parts operating to advance the pieces of material into position for packing and for thereupon exerting the 80 packing thrust thereon is arranged above the work-support. It comprises two side strips *j* attached to angle-irons *k* on the machine *a* by bolts *l* and rigidly connected at their outer ends by the cross-strip *m* and at suitable intervals between their ends by the cross-pieces *n* *n*; the bolts penetrate slots *o*, and upon loosening them the frame may be 85 adjusted longitudinally, or up and down pivotally. The pivotal adjustment of the 90 frame, to vary the elevation of its outer end with reference to the work-support, is effected by adjusting the screws *q* after releasing other screws *r* (Figs. 2 and 4), screws *q* being tapped into a cross-plate *s* 95 (attached to the work-support) and bearing against the foot-pieces *t* (attached to the frame strip *j*) and screws *r* being tapped into the cross-plate and penetrating slots *u* extending longitudinally of the frame. 100

The said frame supports a horizontal peripherally grooved roller *v* at its outer end, the arbor *w* for the roller having its ends fitted in bushings *x* set in upwardly open recesses *y* in the strips *j*. A taut continuous apron or belt *z* extends around the lower roll *b* and the roller *v*, reposing in the grooves thereof and being of such thickness that its outer face is flush with the surfaces of roller *v* both sides of its groove. A strip- 110

per, consisting of a plate 2 depending tangentially from the front side of the roller and having its ends 3 bent off and extended between the ends of the roller and the bushings, is secured in place with its upper edge in close proximity to the roller and the belt by having its said ends 3 penetrated by the arbor *v* and one (or each) of them also penetrated by a screw 4 tapped 10 into one (or each) of the strips *j*. The belt can be tightened by the longitudinal adjustment afforded the frame by the slots *o*. The mounting of the bushings *x* is such, as will be obvious, as to permit the roller to 15 be readily unshipped.

Against the face of the cross strip *m* adjoining roller *v* there are secured, by the horizontal slot-and-screw means 5 shown in Fig. 7, a pair of cheek pieces 6 which 20 have depending plates 7. The cheek pieces, by virtue of the means 5, are adjusted so that their plates 7 will form guides for the inner carton member *C* which, as will be explained, is advanced into the outer carton member 25 *D* as the packing proceeds; their upper ends are rounded at the inside, as at 8, Fig. 7. A block 9 is also secured to the cross-strip *m* against the face thereof adjoining the roller, being between the cheek pieces. The 30 cheek pieces, the stripper 2 and block 9 in effect form a downwardly delivering chute through which the labels, lying flatwise on the belt as they are carried thereby from the rolls *b b*, are delivered edgewise toward the 35 work-support. For a reason to be explained, the face of the block which adjoins the roller *v* is beveled upwardly and forwardly.

10 is a plunger whose stem 11 is arranged 40 to reciprocate horizontally in the cross pieces *n n*, being kept from turning by a cross-head 12 secured on said stem and bearing against the strips *j*; the plunger is normally held with its rear end bearing against the 45 arm *e* of the lever *d²* by spring 14 interposed between the cross-head 12 and the relatively outer cross-piece *n*. The front face of the plunger is beveled upwardly and rearwardly. The backward thrust of the plunger under pressure of its spring is limited 50 by a collar 15 on its stem so that when fully back the beveled face of the plunger is a trifle back of the beveled face of the block 9. The plunger being timed to assume its backward limit on each downward delivery of a 55 label from the chute, the bevel of block 9 assures the label being deflected rearwardly to come edgewise against the bevel face of the plunger and then deflected by the beveled face of the latter to come to rest lying 60 flatwise against said bevel face of the plunger and edgewise with reference to the work-support; this, while not indispensable, is important in the handling of material of so 65 light a character as labels and the like, in

that it contributes to their proper placement in upstanding relation ahead of the plunger.

A retainer device in the form of a plate 16 pivotally suspended from the cross-strip *m* so that it normally stands in an almost horizontal position (Fig. 2), its rear edge in proximity to the retracted plunger, serves as will appear to prevent each label when delivered from the chute from possibly falling forward instead of remaining edgewise and 70 also to support the pack of labels at the back thereof during the back strokes of the plunger. When the plunger advances it is pushed out of the way thereby, swinging into the position shown by full lines in Fig. 4. 80

Operation: When the carton members *B* and *C* have been positioned for beginning the packing operation as already stated, carton member *C*, standing then considerably withdrawn from carton member *B*, has the 85 plunger 10 in telescoped relation thereto. The thrusts of the plunger are timed with reference to the feeding of the labels, which come at substantially regular intervals from the rolls *b b*, so that the beveled face of the plunger is in about the dotted line position of Fig. 4 when each label is delivered downwardly from the chute into the carton member *C*. Owing to the beveling of the faces of block 9 and the 90 plunger as a rule each label when delivered will stand edgewise in the box somewhat canted against the beveled face of the plunger; should it happen to tilt the other way, the retainer device 16 will prevent it from 95 falling flat, in which position it would of course be crumpled up when the plunger performs its packing thrust and necessitate 100 interruption of the packing operation for the purpose of removing it. On delivery of 105 each label the plunger performs its packing thrust, advancing the label toward the closed end *C'* of the carton member *C* which in effect forms a pack-abutment yielding to the plunger; for it will be observed that on each 110 packing thrust the carton member *C* is advanced into carton member *B*, such advance continuing step by step until, the limit of capacity of member *C* having been reached, said member is completely sheathed by member *B*, whereupon the operation being stopped by arresting machine *a* and hence its cam-shaft *c*, the carton is removed and an empty one substituted. Each time the plunger retreats, the retainer-device 16 falls 115 into the position shown in Fig. 2, thus supporting the pack at the back and serving to prevent the possible tilting forward of the next label to be delivered downwardly from the chute, as explained. 120

The mechanism is adapted to suit labels of different lengths by adjusting the cheek-pieces 6 to alter the space between them—in the present instance by setting them apart so that the carton member *C* will just fit 130

between the plates 7. The frame which supports the roller *v* and the plunger, being a part of the main frame structure of the mechanism, is adjustable, as explained, up 5 and down (around bolts *l* as an axis) to center the plunger with reference to the pack whatever the width, *i. e.*, vertical dimension, of the labels.

Having thus fully described my invention, 10 what I claim as new and desire to secure by Letters Patent is:—

1. A mechanism for packing already separated pieces of sheet material including, in combination, a frame structure, means to pack the pieces of material including a plunger movable back and forth substantially horizontally, a downwardly delivering chute arranged over the path of movement of the plunger and having a rearwardly facing 15 forwardly and upwardly inclined feed surface disposed forward of the forward face of the plunger when the latter is at its rearward limit, and means to deliver the pieces each edgewise against said side of the chute.
2. A mechanism for packing already separated pieces of sheet material including, in combination, a frame structure, means to pack the pieces of material including a plunger movable back and forth substantially 20 horizontally, a downwardly delivering chute arranged over the path of movement of the plunger and having a rearwardly facing forwardly and upwardly inclined feed surface disposed forward of the forward face 25 of the plunger when the latter is at its rearward limit, and means to deliver the pieces each edgewise against said side of the chute, said plunger having its forward face inclined upwardly and rearwardly.
3. In combination, a frame structure including a substantially horizontal work-support, means to advance the pieces of material successively first edgewise substantially 30 horizontally and above the support and then edgewise downwardly thereto, and means to thereupon move each piece flat-

wise in a given direction over the support to thus form a pack of the pieces.

4. In combination, a frame structure including a substantially horizontal work-support, and means arranged over and adjustable toward and from the work-support for assembling the pieces of material in a pack including means to move each piece flatwise in a given direction over the support to thus form the pack and means to feed the pieces successively edgewise into the control of the second-named means. 50

5. In combination, a frame structure, means to pack the pieces of material having a substantially horizontal packing thrust, and means to forward the pieces successively over the first means and substantially longitudinally of, and then edgewise into, its 55 line of packing thrust. 60

6. In combination, a frame structure, means to pack the pieces of material having a substantially horizontal packing thrust, and means to forward the pieces edgewise successively over the first means and substantially longitudinally of, and then edgewise 65 into, its line of packing thrust. 70

7. In combination, with the coacting rolls *b b* of a folding machine, means to advance therefrom and thereupon pack the pieces of material passing between said rolls including an endless belt extending around and driven by one of said rolls. 75

8. In combination, with a work-support and with means to deliver the pieces of material edgewise substantially horizontally, means, arranged over said support and pivotally adjustable toward and from the same on an axis near said delivery means, for advancing the pieces of material from the delivery means and delivering them edgewise to the support and for thereupon moving each piece flatwise in a given direction over the support to form the pack. 80

In testimony whereof I affix my signature. 85 90

CORNELIUS JORDAN.
